UNITED STATES PATENT OFFICE.

VIOLET O'ROURKE, OF EXETER, NEW HAMPSHIRE.

TRAP-NEST.

1,318,105.

Specification of Letters Patent.

Patented Oct. 7, 1919.

Application filed April 4, 1919. Serial No. 287,391.

To all whom it may concern:

Be it known that I, VIOLET O'ROURKE, a citizen of the United States, residing at Exeter, in the county of Rockingham and

5 State of New Hampshire, have invented certain new and useful Improvements in Trap-Nests, of which the following is a specification.

This invention relates to improvements in 10 trap-nests, and has for its object to provide means in a device of this character whereby the hen automatically closes the entrance door behind her when she enters the nest, and automatically opens the entrance door in a set position when she leaves the nest by the exit door.

With the foregoing and other objects in view which will appear as the description proceeds, the invention resides in the combination and arrangement of parts and in the detailed construction hereinafter described and claimed, it being understood that changes in the precise embodiment of invention hereinafter disclosed can be made 25 within the scope of what is claimed without departing from the spirit of the invention.

These objects are attained by the means illustrated in the accompanying drawing, in which:—

30 Figure 1, is a perspective view of the improved nest showing both of its doors closed in full lines and in open position in dotted lines.

Fig. 2, is a view of the nest with one of 35 its vertical sides removed to show the inside of the nest, and Fig. 3, is a detail perspective view of the prop-lever for the entrance door, and Fig. 4, is a view similar to Fig. 2, showing another form of prop-lever and a 40 closed bottom for the nest.

Similar reference numerals in all of the figures of the drawing designate like parts.

The housing of the nest is constructed of sides 5, and a top wall 6, secured together 45 along their contacting edges in any suitable manner, and brace connections 7 secured across the open ends of the housing and to the lower edges of the side-walls. At each end ground-sills are secured to the under 50 edges of the side-walls at both sides of the open ends, and these ground-sills project beyond the open ends a considerable distance and are connected together at their outer ends by the platforms 8. As thus constructed 55 the nest is formed without a bottom wall, thereby avoiding the accumulation of dirt

in the housing, and at the same time providing a housing which can be bodily removed from over a setting hen whenever it is desired.

At one end of the housing an entrance-door 9 is provided, the same being pivoted on a rod 10 in a manner to swing freely inward, its outward movement being limited by a stop-block 11 which is firmly secured to 60 and projects inwardly from one of the side-walls, so that the door 9 will contact therewith when it reaches its closed position. At the opposite end of the housing to the entrance door is provided an exit-door 12 pivoted in a like manner as is the door 9, but mounted to swing outwardly only, its inward movement being limited by a stop 13. Thus the two doors are mounted alike to swing in the same direction, but one swings 70 inwardly in respect to the housing and the other one swings outwardly, so that a hen can enter the nest by one door only, and leave the nest only by the other door.

The two doors are connected together 80 preferably by a flexible connection 14, so that when the exit door is operated outwardly, it pulls the entrance-door inwardly or to the set position, and at the same time, the exit door also operates a prop-lever 15 85 which engages under the edge of the entrance-door to support it in the set position. Prop-lever 15 is pivoted at one end to one of the side-walls on the interior of the housing, as indicated at 16, and is preferably 90 constructed larger at its free end to add weight thereto, so that it will readily fall by gravity to unsupporting position when the weight of the entrance door is released therefrom. This prop-lever is also provided with 95 a groove 17 which is formed along the top edge and around the pivot end of the lever, said groove 17 being adapted to seat one end of a flexible connection 18 which is connected at its other end to the exit door 12. The 100 groove 17 is formed sufficiently deep to retain the operating cord 18 in engagement with its periphery, and to further guide the operating cord 18, an eye 19 is secured to the side-wall adjacent the lever 15.

The prop-lever is also provided with a lip 20 at its free end, said lip being adapted to engage the bottom edge of the entrance-door when it is in the set position, and thereby prevent the prop-lever from being 110 thrown too far in one direction. When both doors are in the closed position, the

free end of the prop-lever is preferably supported by the guide-eye 19.

In operation, the trap-nest is initially set manually by pulling the exit-door outwardly. This pulls the flexible connections 14 and 18 and consequently the entrance-door and prop-lever are swung to the dotted line position shown at 21, and then the exit-door is released and closes by gravity. In 5 the set position, the lower edge of the entrance door is supported so low that the back of the hen entering the nest will slightly raise the door. This at once relieves its weight from the prop-lever 15, and it falls 10 from the supporting position, and as soon as the hen passes from beneath the door, it also automatically falls to the closed position against the stop 11, thus closing the entrance behind the hen. When the hen 15 desires to leave the nest, she will discover that with a little force against the exit door it will open outwardly and allow her to escape, and as she raises the exit-door to escape, it will operate both the entrance-door 20 and its prop-lever to the set position for the next hen. The length of the flexible connections 14 and 18 are of course determined 25 by the amount of movement to be given the entrance door and the prop-lever, and as 30 shown in the drawing the connection is such, that the entrance-door will start to move inwardly at once with the outward movement of the exit-door, and while the doors are raising, the slack in the connection 18 is 35 being taken up, so that at the end of the raising movement of the doors, the prop-lever will be operated quickly to the supporting position beneath the edge of the entrance-door. Any suitable nest can be 40 prepared for the hens on the interior of the trap, usually a layer of straw is provided on the ground floor. While the drawing 45 shows solid doors it will be understood that any suitable screen doors can be used. In the solid doors used, ventilating openings 50 45 55 60 65 70 75 80 85 90 95 100 105 110 115 120 125 130 135 140 145 150 155 160 165 170 175 180 185 190 195 200 205 210 215 220 225 230 235 240 245
